H. F. CARY, OF BOSTON, MASSACHUSETTS.

Letters Patent No. 83,927, dated November 10, 1868.

IMPROVEMENT IN MACHINES FOR APPLYING REINFORCING-PATCHES TO BUTTON-HOLES OF COLLARS.

The Schedule referred to in these Letters Patent and making part of the same.

To all whom it may concern:

Be it known that I, H. F. CARY, of Boston, in the county of Suffolk, and State of Massachusetts, have invented an Improvement in the Manufacture of Paper Collars; and I do hereby declare that the following, taken in connection with the drawings which accompany and form part of this specification, is a description of my invention sufficient to enable those skilled in the art to practise it.

In the use of paper collars, as articles of wearing or dress-apparel, one obstacle to their success or endurance is the tendency of the button-holes to "tear out," the paper not having strength, in itself, sufficient to resist the strain brought at the angles of the button-holes, without giving way.

To obviate this difficulty, the paper is sometimes strengthened at those surfaces, or portions of surface, where the button-holes are or are to be cut, by cementing thereto patches of cloth or paper; and my invention relates to the manner of applying these reinforcing-patches.

Before my invention, it was generally the practice to apply these patches by hand, patch by patch, and, besides the time consumed by such process, it was difficult to always place the patches just in proper position for surrounding the holes to be cut; and my invention consists, primarily, in the employment of ribbons, each having a cement-applied surface, these ribbons travelling over the collar-paper, (before it is punched into collars or collar-blanks,) at the centre and near the opposite edges of the paper, or in lines where the button-holes are to be cut, so that, by the action of a punch and die to cut out the patch, and a follower to press the patch down upon the surface of the paper, the patches shall be cemented to the paper in proper position, the cement-applied surface of the ribbons being moistened before the dies operate, so that the patches shall adhere to the paper.

The drawings represent a machine for cutting out and applying the button-hole reinforcing-patches, in accordance with my invention, the mechanism being shown in connection with the mechanism for stamping out the collar-blanks and the button-holes.

A shows the machine in side elevation.

B is an end view of the same.

C shows a portion of the collar-paper, with the patches affixed thereto.

a denotes the frame, at one end of which are the ordinary button-hole punches, b, and collar or collar-blank punches, c. At the opposite end of this frame a loose shaft, d, is mounted in suitable bearings, this shaft carrying three drums or spools, e, having wound upon them ribbons, f, from which are cut the button-hole patches, each ribbon being preferably made of cloth, and having one dry cement-applied or gummed surface.

Under the shaft d is a trough, g, for holding water, and over the trough is a loose shaft, h, carrying three wallowing-rolls, i, the peripheries of which dip into the water, so that their surfaces are kept wet by rotation of the shaft. On the opposite sides of the shaft h are guide-rolls, k, l, and the ribbon from each spool e passes under the front roll, k, over one of the wallowing-rolls i, underneath the roll l, its cement-applied surface being thereby brought into contact with the wet surface of the roll i, to make such surface adhesive.

j denotes the collar-paper, passing from a suitable roll or paper-cylinder, up and over three bed-plates or flat disks, m, and thence over a platform, n, to the button-hole and blank-cutting mechanism.

o denotes a vertically-reciprocating carriage, sliding between ways, p, and jointed to pitmen, q, hung upon crank-pins r, on the ends of a crank-shaft, s. To this carriage are fixed three punches, t, arranged directly over the bed-plates m, and working through die-plates u, between the lower surface of which and the bed-plates m, the collar-paper passes, as seen at A, while beneath each punch, and between the upper surface of each die-plate and the under surface of the die-head or stock v, one of the patch-ribbons f passes, as seen at A.

Each die-plate has a die-matrix or female die corresponding to the end of the punch above it, and to the form which the button-hole reinforcing-patch is to have, and at each descent of the carriage o, each punch t is carried through the die beneath it, cutting a patch from the ribbon in its descent, and carrying such patch down against the collar-paper beneath it, forcing the patch and paper against the bed-plate, and thereby causing the cement-applied and moistened patch to adhere to the paper, as will be readily understood.

The three punches t are arranged at distances apart corresponding to the positions at which the end and centre button-holes are to be formed, and each punch is preferably made oblong or oval, and so arranged that the end patches are applied lengthwise of the collar-blank to be cut, and the centre one crosswise, as shown at C, so as to correspond to the oblong form of each button-hole.

Each patch-ribbon f, after passing over the bed-plate m, (that is to say, after having the patch cut from it,) passes under a guide-roll, x, thence up between a pair of draw-rolls, y, and thence around a waste-roll, z, as seen at A.

The roll s is connected to and driven from the crank-shaft s, by a band, a², passing around pulleys on the shaft and roll, this band being, however, sufficiently loose to slip on the pulley on roll z if the ribbon is held back by the draw-rolls y.

The rolls y have an intermittent positive movement imparted to them, so that they shall cease to draw the ribbon while the patch-cutting punches are descending, this intermittent motion being derived as follows:

On the end of the lower shaft, y , is a gear-pinion, b^2 , which meshes into and is driven by a gear-wheel, c^2 , mounted on a short shaft, d^2 , projecting from the frame A. This gear c^2 carries a series of pins, e^2 , into which engages, at proper times, a sliding latch or hook, f^2 . The shank of this hook slides vertically through a suitable guide or guides, and is connected at its lower end, by a spring, g^2 , with the frame a , this spring holding the hook-shank, or an arm, h^2 , thereof, up against the periphery of a cam, i^2 , on the crank-shaft s . As the shaft s , in its ascent, carries up the punches t , the cam i^2 presses down the hook, which, being hooked upon one of the pins, e^2 , will thereby impart rotative movement to the lower draw-roll, which will draw forward the patch-ribbon, the roll z turning at the same time, and winding the waste-ribbon upon it.

When the punches descend, however, the hook-shank will be carried up by the spring g^2 , and an incline, k^2 , will cause the hook to slip out by the next pin above it, passing which, it will slip in over such pin.

The collar-paper, with the patches cemented upon its upper surface, is fed along by suitable mechanism, and passes forward to the operation of the button-hole punches b and the punches c , which cut out the collar-blank.

It will thus be seen that the collars are automatically provided with button-holes having reinforced

edges, and that these patches are applied while the paper is in sheet-form, or before the button-holes or collar-blanks are cut out.

The mechanism may, of course, be varied, but I consider that a mechanism, substantially as shown, is the best to use.

As the centre patches cover less space, in the direction of the length of the collar-paper, than the side ones, provision may be made for taking up the side strips or waste ribbon, after the patches are cut, a little faster than the centre strip, and this provision I have made in a machine now in use.

Instead of cloth ribbons for the patches, paper strips may be employed, but I consider the cloth preferable.

I claim the process herein described, of applying to paper, before or after its conversion into collars, reinforcing button-hole patches, automatically cut from gummed strips, continuously moistened in their passage through the machine, substantially as described.

I also claim, in a machine for applying strengthening-patches to button-holes of collars, a trough and guides, for moistening the cement-applied surface of the ribbon.

H. F. CARY.
